RAILWAY TRUCK

Donald S. Barrows, Rochester, N. Y., assignor to
The Symington Company, New York, N. Y., a
corporation of Maryland

Application April 1, 1932, Serial No. 602,589

16 Claims. (Cl. 105—197)

This invention relates to trucks for railway rolling stock and, more particularly, to the construction of the side frames, bolsters and associated parts, as well as the formation and arrangement of the bolster supporting springs.

The principal object of my invention, generally considered, is the provision of trucks for railway rolling stock utilizing both plate and coil spring means for the support of the associated bolsters.

10 Another object of my invention is the provision of a railway truck in which a single elliptic spring is disposed outside of and parallel to the frame resting on an outboard extension from the tension member of said frame for the support of an associated bolster.

15 A further object of my invention is the provision of coil springs associated with the elliptic spring above referred to for the support of the bolster, said coil springs being disposed back of the elliptic spring in the bolster opening and desirably placed so as to balance the elliptic spring about the longitudinal center line of the frame.

20 A still further object of my invention is the provision of a truck in which the side frames support bolster springs comprising both plate and coil means, said side frames having extensions underlying those portions of the spring means disposed beyond the bolster opening, said extensions being recessed on their upper surfaces to receive a portion of the plate spring means for properly positioning the same, the supported bolster being correspondingly recessed for receiving the corresponding upper portion of the plate spring means.

25 30 35 An additional object of my invention is the provision of a nest of coil springs disposed between plates with a fastening bolt and an elliptic spring associated therewith but not retained by said plates, whereby said coil springs may be placed in position for the support of a bolster separately from the associated elliptic spring.

40 45 Other objects and advantages of the invention relating to the particular arrangement and construction of the various parts will become apparent as the description proceeds.

Referring to the drawings illustrating my invention:

Figure 1 is a partial side elevation and partial longitudinal section on the line 1—1 of Fig. 2, showing a portion of the side frame of a truck with its associated spring plank, bolster, nest of coil springs disposed between associated plates, and elliptic or plate spring positioned outwardly thereof.

50 55 Figure 2 is a fragmentary horizontal view on

the line 2—2 of Figure 1, looking in the direction of the arrows.

Figure 3 is a view corresponding to Figure 2, but showing a modification.

Figure 4 is a view corresponding to Figure 2, but showing another modification.

Figure 5 is a view corresponding to Figure 1, showing a modified arrangement in which a different form of side frame is employed.

Figure 6 is a horizontal sectional view on the line 6—6 of Figure 5, looking in the direction of the arrows.

Figures 7 and 8 are views corresponding, respectively, to Figures 1 and 2, but showing a truck not using a spring plank and omitting to use plates for the nest of coil springs.

Figures 9 and 10 are views corresponding, respectively, to Figures 7 and 8, but showing a different form of side frame.

Figure 11 is a view corresponding to Figure 2, but showing a modification.

Figure 12 is a view corresponding to Figure 2, but showing another modification.

Referring to the drawings in detail, like parts being designated by like reference characters, and first considering the embodiment of my invention illustrated in Figures 1 and 2, there is shown a portion of a truck comprising a side frame 1, preferably formed of cast steel, although it will be obvious that certain advantages of my invention may be obtained when using frames of other than cast construction. The frame 1 comprises a compression member 2, a tension member 3, and bolster guide columns or strut portions 4, spacing intermediate portions of said compression and tension members, leaving a window opening 5 therebetween. The compression and tension members extend outwardly to unite with each other and associated journal boxes (not shown) beyond the guide columns, as will be understood.

The tension member 3 between the bolster guide columns is preferably generally box-shaped in section and comprises an upper web 6 forming a spring seat portion, a lower web 7, and side webs 8. The upper web 6 is desirably extended outwardly and inwardly, as indicated at 9 and 10, to provide an adequate spring-seating area, and the side webs 8 are desirably bulged, as indicated at 11, beneath said extensions for properly supporting the same.

In the present embodiment, a spring plank 12 is employed which rests on the spring plank seat portion 6 of the frame and is interlocked therewith, as by means of squaring lugs 13 on said frame entering corresponding apertures 14 in the

plank. A nest of springs, generally represented by the reference character 15, rests on said plank and, in turn, serves for the support of the bolster 16. Said bolster, in the present embodiment, is formed with lugs 17 interlocking with the bolster guide columns when in normal or elevated position, as illustrated, and adapted to be inserted or removed when lowered to a position between the outwardly offset portions 18 of the bolster guide columns, as will be understood.

In the present embodiment, the nest of springs 15 serving to support the bolster 16 from the frame 1 comprises a plate or elliptic spring device 19 which, in the present embodiment, comprises two groups of spring plates 20 arranged in stepped formation, as usual, held by upper and lower spring bands 21 and 22, and with their ends engaging end blocks 23. In the present embodiment, the spring plank 12 is apertured, as indicated at 24, to receive the lower spring band 22, and the bolster is formed with a downwardly opening recess 25 receiving the upper spring band 21, whereby said elliptic spring 19 is held in proper position outwardly of and substantially parallel to the frame 1 and supported by the outboard extension of the tension member 3. The spring plank 12, which is desirably formed channel-shape in section with a lower web and upstanding flanges, desirably has the flanges cut away or decreased in height beneath the elliptic spring 19, as indicated at 36, to avoid interference between the elliptic spring and spring plank even when the spring is compressed.

Supplementing the elliptic spring 19 is a nest of helical or coil springs 26, which nest, in the present embodiment, comprises three double coil A. R. A. bolster springs 27 mounted between a lower spring plate 28 and an upper spring plate 29, said plates having spring positioning collars 30 about which the inner coils of the springs 27 fit and nibs or bosses 31 which engage corresponding pockets in the spring plank and bolster, respectively, for holding said plates in proper position. A bolt 32 and associated nut 33 desirably serve for retaining the plates in proper position, whereby the helical springs may be assembled for application and removal as a unit. The spring plates are not formed large enough to receive the elliptic spring 19, because it is considered desirable to apply and remove the coil springs separately from the elliptic spring, thereby avoiding the necessity of handling the entire weight and size of the nest of springs at one time. The coil spring nest 26 is desirably of such capacity and so positioned that the normal bolster supporting force thereof balances that of the elliptic spring about the longitudinal center line or plane of the associated frame. Although only one frame has been illustrated, it will be understood that the other ends of the bolster and spring plank are received in a corresponding bolster or window opening in a companion frame on the other side of the truck.

Referring now to the embodiment of my invention illustrated in Figure 3, a construction is there disclosed which is identical with Figure 2 except that the nest of helical or coil springs 26^a supported on the plank 12^a for the support of the bolster 16^a from the frame 1^a is arranged with the apex of the triangle pointed inwardly, or toward the center of the truck, rather than outwardly, and correspondingly adjusted in position so as to balance the elliptic spring 19^a.

Referring now to the embodiment of my invention illustrated in Figure 4, a construction is there

disclosed which is identical with that of Figures 1 and 2 except that the nest of coil or helical springs 26^b comprises four rather than three double coil springs 27^b provided with correspondingly modified plates and resting on a plank 12^b for the support of a bolster 16^b, the position of said nest of springs being correspondingly changed, as compared with Figures 1 and 2, so as to balance the associated elliptic or plate spring 19^b about the longitudinal center line or plane of 10 the frame 1^b.

Referring now to the embodiment of my invention illustrated in Figures 5 and 6, a construction is there disclosed which substantially corresponds with Figures 1 and 2, except that a frame 15^c of the type described and claimed in my Patent No. 1,652,808 of December 13, 1927 is utilized, the spring plank 12^c being correspondingly modified to interlock with the upward convolutions or reinforcements 34 and the helical springs 27^c being employed without spring plates and held in position by squaring lugs 13^c on the frame extended up through the plank 12^c to provide spring positioning means for the inner coils of the springs 27^c. The bolster 16^c is desirably provided with 25 corresponding depending lugs 35 serving for positioning the upper ends of the springs 27^c, said springs being arranged in triangular formation, like the springs of the embodiment of Figures 1 and 2, and positioned so as to balance the elliptic 30 spring 19^c about the longitudinal center line or plane of the frame 1^c.

Referring now to the embodiment of my invention illustrated in Figures 7 and 8, a construction is there disclosed corresponding with that of 35 Figures 1 and 2, except that no spring plank or plates are employed, the springs 27^d being held in position by spring-centering lugs 13^d and 35^d, as in the embodiment of Figures 5 and 6, with the springs positioned so as to balance the elliptic 40 spring 19^d about the longitudinal center line or plane of the frame 1^d, said coil and elliptic or plate springs assisting one another for the support of the bolster 16^d.

Referring now to the embodiment of my in- 45 vention illustrated in Figures 9 and 10, a construction is there disclosed which is substantially identical with that of Figures 5 and 6, except that spring plates 28^e are utilized for the springs 27^e, said plates being held together and positioned 50 like those illustrated in Figures 1 and 2, the nest of coil springs 26^e being positioned so as to balance the associated elliptic or plate spring 19^e about the longitudinal center line or plane of the associated frame 1^e for jointly supporting the 55 bolster 16^e.

Referring now to the embodiment of my invention illustrated in Figure 11, a construction is there disclosed which corresponds with that of Figures 1 and 2, except that only one helical 60 spring unit 27^f is employed without any spring plate and positioned far enough inward to balance the associated elliptic spring 19^f, both of said springs being utilized with a spring plank 12^f and serving jointly for the support of an associated bolster 16^f from a frame 1^f.

Referring now to the embodiment of my invention illustrated in Figure 12, a construction is there disclosed which corresponds with that 70 of Figure 11, except that two or more double coil springs 27^g are utilized and arranged on the longitudinal center line of the associated spring plank 12^g, said springs being positioned so as to balance the associated elliptic spring 19^g for 75

assisting in the support of the bolster 16 from the frame 12.

Although in all of the embodiments of my invention disclosed I have shown the use of double coil spring units, it will be understood that, if desired, some, or all, of said units may be single coil, to thereby correspondingly decrease the capacity of the bolster springs. It will also be understood that, although in some instances I have shown the use of plates with the helical or coil spring units, and not in others, plates may or may not be used with any form of my invention in accordance with circumstances, as may be desired. It will also be noted that although in some forms of my invention I have shown the use of spring planks, while omitting to show planks in other forms, I may or may not use a spring plank with any form of my invention, as may be considered advisable.

From the foregoing disclosure, it will be seen that I have devised a railway truck in which plate or elliptic spring means, preferably a single elliptic spring, is disposed outside of and parallel to the frame, resting on an outboard extension 25 of the tension member for the support of an associated bolster, said spring being desirably assisted by coil or helical springs positioned so as to balance the distribution of load about the longitudinal center line or plane of the associated frame.

Although preferred embodiments of my invention have been illustrated, it will be understood that modifications may be made within the spirit and scope of the appended claims.

35 I claim:—

1. In a railway truck, in combination, a side frame formed with compression and tension members spaced at intermediate portions by spaced bolster guide columns, a bolster extending into the space between said columns, and projecting outwardly beyond said frame, plate spring means operatively interposed between said frame and bolster and overlapping said columns on the outer side of the frame, and coil spring means operatively interposed between the bolster and side frame inwardly of said plate spring means, and at least some of such capacity and disposed inwardly at such a distance from the longitudinal central plane of the frame that it balances the distribution of load about said plane.

2. In a railway truck, in combination, a side frame formed with compression and tension members spaced at intermediate portions by spaced bolster guide columns, a bolster extending into the space between and interlocked with said columns, and projecting outwardly beyond the outer side of the frame, plate spring means operatively interposed between the side frame and bolster and overlapping said columns on the outer side of said frame, and coil spring means, at all times assisting said plate spring means, operatively interposed between the bolster and side frame inwardly of said plate spring means in transverse alignment with the space directly between said bolster guide columns, and extended inwardly of said space, and of such capacity and disposed at such a distance from the longitudinal central plane of the frame that it balances the distribution of load about said plane.

3. In a railway truck, in combination, an integrally cast side frame formed with compression and tension members spaced at intermediate portions by bolster guide columns leaving a window opening therebetween, a bolster extending into said window opening and projecting out-

wardly beyond the outer side of the frame, plate spring means underlying that portion of the bolster projecting beyond said frame, the tension member beneath the bolster being provided with spring seat portions integral therewith and which project outwardly to underlie said plate spring means for the support thereof, and coil spring means, acting in parallel with said plate spring means, operatively interposed between the bolster and side frame inwardly of the plate spring means, and at least some of such capacity and disposed inwardly at such a distance from the longitudinal central plane of the frame, that it balances the distribution of load about said plane.

4. In a railway truck, in combination, a side frame formed with an outboard extension on a lower member thereof, plate spring means, comprising leaves held by band means, resting on said extension and disposed parallel to said frame, coil spring means supported on said frame inwardly of said plate spring means, said coil spring means being formed with upper and lower plates held together by fastening means, whereby they may be handled as a unit, and a bolster supported by said plate spring and coil spring means, said bolster having a recess receiving said band means.

5. In a railway truck, in combination, a side frame formed with compression and tension members spaced at intermediate portions by bolster guide columns leaving a window opening therebetween, a bolster with an end portion received in said window opening and projecting outwardly beyond the outer side of said frame, plate spring means underlying that portion of the bolster projecting beyond said frame and disposed entirely outwardly of said guide columns, the tension member beneath said bolster being provided with a spring seat portion which projects outwardly to underlie and directly engage said plate spring means, and coil spring means operatively interposed between said bolster and side frame, positioned inwardly of the plate spring means and at least some of such capacity and disposed inwardly at such a distance from the longitudinal central plane of the frame, that it balances the distribution of load about said longitudinal central plane.

6. In a railway truck, in combination, a side frame formed with a bolster opening defined by a tension member having an outboard extension, plate spring means resting on said extension and disposed parallel to said frame, coil spring means disposed in said opening, and other coil spring means disposed inwardly of said opening and said first-mentioned coil spring means so as to balance the distribution of load about the longitudinal center line of the frame, and a bolster supported on said plate and coil spring means.

7. In a railway truck, in combination, a side frame formed with a tension member having an outboard extension thereon, a spring plank with an end portion resting on said tension member and extension, plate spring means comprising leaves held by spring bands resting on said extension and disposed parallel to said frame, coil spring means supported on said plank inwardly of said plate spring means, said coil spring means being formed with upper and lower plates held together by fastening means whereby they may be handled as a unit, and a bolster supported by said plate and coil spring means.

8. In a railway truck, in combination, a side frame formed with a bolster opening defined by a tension member having outboard and inboard

- extensions, plate spring means resting on one of said extensions and disposed generally parallel to said frame, coil spring means disposed in said opening, other coil spring means supported by 5 said other extension so as to balance the distribution of load about the longitudinal center line of the frame, and a bolster supported by said plate and coil spring means.
9. In a railway truck, in combination, a side frame formed with a bolster opening, the lower portion of said opening being defined by the upper web of a tension member, said upper web having outboard and inboard extensions, plate spring means resting on one of said extensions, 10 disposed generally parallel to said frame, and entirely to one side of the portions above said tension member, coil spring means at least a portion of which is supported by said other extension and of such capacity and disposed at such 15 distance from the longitudinal central plane of the frame, as to balance the distribution of load about said longitudinal central plane, and a bolster supported by said plate and coil spring means.
10. In a railway truck, in combination, side frames formed with bolster openings each defined by a tension member having outboard and inboard extensions, plate spring means resting directly on one of said extensions of each frame 20 and disposed entirely to one side of the portions of said frame above its tension member, coil spring means supported by the other extension of each frame and of such capacity and disposed at such a distance from the longitudinal central 25 plane of the frame, that it balances the distribution of load about said plane, and a bolster supported by said plate and coil spring means and interlocked with the frames.
11. In a railway truck, in combination, a side frame formed with a tension member having an outboard extension, an elliptic spring supported by said extension and disposed parallel to said frame entirely beyond the portions thereon above said tension member, coil spring means supported by 30 said frame inwardly of said elliptic spring, said coil spring means being formed with upper and lower plates held together by fastening means whereby it may be handled as a unit, and a bolster supported by said elliptic spring and coil spring means.
12. In a railway truck, in combination, a side frame formed with an outboard extension from a lower member thereof, an elliptic spring resting on said extension, disposed parallel to said frame, and positioned entirely beyond the portions of 35 said frame above said extension, coil spring means supported on said frame inwardly of said elliptic spring and assembled for handling as a unit independently of said elliptic spring, and a bolster supported on said elliptic spring and coil spring means and formed with a recess receiving a portion of said elliptic spring.
13. In a railway truck, in combination, a side frame having a compression member, a tension 40
- member, bolster guide columns connecting intermediate portions of said compression and tension members and spaced to leave a bolster opening therebetween, portions of said tension member being upwardly embossed to form diagonal 45 reinforcements intersecting the lower corners of said bolster opening, the upper web of said tension member beneath said bolster opening being extended outwardly beyond the guide columns, an elliptic spring supported on said extension and disposed generally parallel to said frame entirely beyond said guide columns, coil spring means supported on said frame inwardly of said elliptic spring and comprising one coil disposed with its axis substantially in the longitudinal 50 central plane of said frame between said reinforcements, a plurality of coils disposed inwardly of said central coil, and a bolster supported on said elliptic spring and all of said coils.
14. In a railway truck, in combination, a side frame formed with a bolster opening defined by a tension member having an outboard extension, an elliptic spring resting on said extension and disposed parallel to said frame entirely beyond the portions thereof above said tension member, 55 a nest of coil springs disposed inwardly of said elliptic spring and comprising a coil with its normally vertical axis positioned substantially in the longitudinal central plane of said frame, a plurality of coils spaced longitudinally of said frame and positioned inwardly of said plane so as to balance the distribution of load about said plane, and a bolster supported by all of said springs.
15. In a railway truck, in combination, a side frame formed with a tension member having an outboard extension, an elliptic spring resting on said extension and disposed parallel to said frame and beyond the portions thereof above said extension, coil spring means supported by 60 said frame inwardly of said elliptic spring and comprising a coil with its normally vertical axis positioned substantially in the longitudinal central plane of said frame, a plurality of coils spaced longitudinally of said frame and positioned inwardly of said central coil so as to balance the distribution of load about said plane, and a bolster supported by said springs.
16. In a railway truck, in combination, a side frame formed with a bolster opening defined by a tension member having outboard and inboard extensions, an elliptic spring resting on one of said extensions and disposed generally parallel to said frame and at one side of the portions thereof above said extensions, and coil spring means 65 with at least a portion thereof supported by said other extension at the other side of the portions of said frame above said extensions and of such capacity and disposed at such a distance from the longitudinal central plane of the frame, as to balance the distribution of load about said frame, and a bolster supported by all of said springs.

DONALD S. BARROWS.
